UNITED STATES PATENT OFFICE.

JOHN O. CARREY, OF ST. LOUIS, MISSOURI, ASSIGNOR TO CARREY ROTORY ENGINE COMPANY, OF ST. LOUIS, MISSOURI, A CORPORATION OF MISSOURI.

ROTARY AIR COMPRESSOR.

Application filed August 2, 1919. Serial No. 314,844.

To all whom it may concern:

Be it known that I, JOHN O. CARREY, a citizen of the United States, residing at city of St. Louis, State of Missouri, have 5 invented a certain new and useful Improvement in Rotary Air Compressors, of which the following is a full, clear, and exact description, such as will enable others skilled in the art to which it appertains to make 10 and use the same, reference being had to the accompanying drawings, forming part of this specification.

My invention relates to an air compressor of the type wherein a pair of rotors having 15 interengaging peripheral portions are mounted for operation within a housing, the principal objects of my invention being to generally improve upon and simplify the existing forms of air compressors of this 20 type and to provide a relatively simple and easily operated apparatus which can be effectively used wherever it is desired to rapidly and economically compress to a relatively high degree of compression air or 25 other fluids.

Further objects of my invention are to provide an improved form of packing which will be effective in minimizing the leakage of fluid from the compressor and, also, to 30 provide improved means for lubricating the operating parts of the apparatus.

With the foregoing and other objects in view, my invention consists in certain novel features of construction and arrangement of 35 parts, hereinafter more fully described and claimed, and illustrated in the accompanying drawings, in which—

Figure 1 is a vertical section taken through the housing of the compressor to 40 one side of the rotors operating therein and showing in section the fluid separator associated with the compressor.

Figure 2 is a horizontal section taken approximately on line 2—2 of Figure 1.

Figure 3 is a vertical section taken approximately on the line 3—3 of Figure 2.

Figure 4 is a horizontal section taken approximately on the line 4—4 of Figure 1.

Figure 5 is a vertical section taken approximately on line 5—5 of Figure 2. 50

Figure 6 is a vertical section taken through the center of a reducing valve that is associated with my improved compressor.

Figure 7 is an enlarged elevational view 55 of a portion of the driving shaft which carries one of the rotors of the compressor.

Figure 8 is a vertical section taken approximately on the line 8—8 of Figure 1.

Figure 9 is an elevational view of a portion of the periphery of one of the rotors. 60

Figure 10 is an enlarged detail section taken approximately on the line 10—10 of Figure 9.

Referring by numerals to the accompanying drawings, 10 designates the body or casing of the compressor, the same being provided with a pair of cylindrical rotor chambers 11, the latter communicating with each other at a central point and removably secured to the ends of this body or casing 70 are heads 12 and 13. These heads are provided with journal bearings 14 for the shafts of the rotors, said journal bearings being provided with bushings 15 and the outer ends of said bearings being closed by caps 75 16 in which are positioned suitable packing rings or gaskets 17. Mounted for rotation in the bearings 14 are the end portions of rotor carrying shafts 18 and 19. Shaft 18 is provided with an axially disposed bore or 80 passageway 20, and shaft 19 has formed therein an axially disposed bore or passageway 19^a. One end of shaft 19 is extended through one of the caps 16 in order to receive a suitable driving connection, and that portion of the shaft 19 that is positioned in the bearing to which the perforated cap is applied is provided with a plurality of grooves 21, adapted to receive a liquid packing such as oil. The outer side 85 face of each groove is straight and disposed at right angles to the axis of the shaft, such construction assisting in providing an effective packing against outward leakage of the oil contained in said grooves. The oil 90 contained in these grooves 21, in addition to

providing a liquid packing for that portion of the shaft which performs the functions of a journal, lubricates said journal within its bearing, and the supply of oil to said grooves passes from the bottom of the adjacent rotor chamber 11 through a duct 21^a, the latter passing through a part of the casing 10, the head 13, and thence through the bearing 14 on said head into the chamber between said bearing and the cap 16 thereupon (see Figs. 5 and 8).

Fixed in any suitable manner on the shafts 18 and 19 within the chambers 11 are rotors 22 and 23 the peripheries of which are provided with ribs or teeth preferably of the herringbone type which intermesh and thereby form a driving connection. The rotors are slightly shorter than the length of the chambers in which they operate and such construction provides a space 24 between the head 13 and adjacent ends of the rotors, a portion of this space being occupied by packing plates 25, the peripheries being provided with suitable packing members 26. The meeting edges of these packing plates are overlapped to form a leak-proof joint 27. These plates are loosely mounted on the shafts 18 and 19 and formed in their inner faces are annular grooves 28 which are concentric with the central openings which receive said shafts 18 and 19. These grooves are adapted to receive fluid under pressure, to counteract to a certain extent, the fluid pressure exerted on the outer faces of said plates and which latter pressure maintains them in close engagement with the adjacent ends of the rotors. These plates 25 constitute a yielding packing which readily accommodates itself to the movement resulting from the expansion and contraction of the rotors.

Formed through each rotor adjacent to its periphery is an annular row of passages 29, there being preferably one passage for each rib or tooth on the rotor and extending from each of these passages radially through the adjacent ribs or teeth to recesses 30. Formed in the outer faces of the latter, are branch passages 31 (see Figures 9 and 10). The passages 29 and 31 and recesses 30 are adapted to contain liquid lubricant which fills said recesses 30 and thus provides an effective liquid packing between the outer faces of the ribs or teeth of the rotors and the inner surfaces of the walls around the chambers 11. Further, this liquid packing or oil serves to lubricate the peripheries of the rotors while the latter are in operation.

Formed in the end face of each rotor concentric with and arranged outside the row of passages 29, is an annular groove 32, and extending therefrom partly across the ends of the teeth or ribs of the rotor are radially disposed branch grooves 33. These grooves

32 and 33 are adapted to contain liquid lubricant, thus providing a lubricating packing between the ends of the rotors and the head 12 and plates 25.

Formed through each rotor and leading from the spaces between two of the ribs or teeth on the periphery thereof to the axially disposed passages 19^a and 20 are radially disposed passages 34 by means of which liquid lubricant is permitted to enter the chambers within the caps on the bearings 14 and 15, thereby providing for the lubrication of said bearings (see Figs. 2 and 8).

Formed in the top of the casing 10 and leading upwardly therethrough from the central point between the chambers 11 is a compressed fluid outlet passageway 35 and leading therefrom to a fluid separator 36 is a tubular connection 37 in which is located a suitable check valve 38 of ordinary construction. This fluid separator may be of any desired construction, but preferably of the type that is provided with an air chamber 39, a separating chamber 40, the latter being provided with inclined baffle plates 41, and a liquid chamber 42, the latter being common to the chambers 39 and 41. Leading from the upper portion of the separating chamber 40 to a compressed air tank or container (not shown) is a tubular connection 43 in which is located a check valve 43^a. Leading from the liquid chamber 42 is a pipe 44 and leading therefrom through the lower portion of head 12 are branch pipes 45. The inner ends of these branch pipes communicate with the chambers 10 at points in the lowermost paths of travel of the adjacent ends of the passages 29 in the rotors and thus the liquid lubricant from chamber 42 is forced into the rotor chambers 11 and into and through the passages 29 (see Figure 4).

The fluid pressure for the chamber 24 to the rear of plates 25 is supplied through a branch pipe 46 which leads from tubular connection 37 and said branch pipe leading through the head 13 at a central point slightly above the horizontal plane occupied by the axes of the shafts 18 and 19 (see Figures 3 and 5). Located in this branch pipe 46 is a suitable pressure reducing valve 46^a, preferably of the type illustrated in Figure 6.

Formed integral with the lower portion of casing 10 and between the lower portions of the rotor chambers 11 is a substantially triangular block 48, the apex of which terminates immediately below the point of interengagement between the teeth or ribs of the rotors, and the side faces of this triangular block are curved to conform to the curvature of the inner faces of the rotor chambers. Formed through the casing below this block is an air inlet passage 47, and leading laterally from the upper portion

thereof through the lower portion of the triangular block 48 are branch passages 49 that lead into the lower portions of the rotor chambers 11. A tubular fitting provided with a check valve 50 is located in the lower portion of the air inlet passageway 47.

In the operation of my improved air compressor, shaft 19 is driven in any suitable manner with the result that the rotors having peripheries which mesh or interengage are driven toward each other in the directions indicated by arrows in Figure 1. Air drawn through inlet passage 47 and branch passages 49 will be trapped in the spaces between the ribs or teeth on the peripheries of said rotors and such trapped air will be carried approximately three-fourths of the distance around the rotor chambers 11 or to the point directly below outlet passage 35 at which point the ribs or teeth on the rotors engage with each other.

These ribs or teeth are formed so that they have a relatively close rubbing fit and consequently very little air passes downwardly between the teeth which are in engagement with each other, and as air cannot escape backwardly between the peripheries of the rotors and the inner surfaces of the chambers 11, said air will be compressed at a point immediately below the passage 35 and in such condition will pass upward through the outlet passageway and from thence through tubular connection 37, past check valve 38 therein and into the air chamber in fluid separator 36.

The air under pressure will pass downwardly through air chamber 39, thence upwardly through the separating chamber 40 and the baffles therein will separate the moisture and oil from this compressed air and the latter will pass from the separator to storage tank, or point of use, through outlet pipe 43 that is provided with check valve 43^a. The pressure within chamber 24 behind the plates 25, and which is necessary to maintain the latter in engagement with the corresponding ends of the rotors, is taken from tubular connection 37 through pipe 46, and after passing through a suitable reducing valve, preferably of the type illustrated in Figure 6, the air at reduced pressure is taken into the chamber 24 and thus maintains the plates 25 in yielding engagement with the ends of the rotors. Inasmuch as the plates 25 are free to move backward and forward upon the shafts 18 and 19, they constitute a floating or yielding packing and a relatively tight joint is maintained between them and the adjacent ends of the rotors even while the same are expanded or contracted under varying degrees of temperature. The pressure against the outer faces of the plates is balanced in proportion to the pressure on their inner faces so as to reduce to a minimum the

mechanical friction between the ends of the rotors and said plates. This counterbalancing effect is obtained by the pressure exerted by the air between the ribs or teeth of the rotors and also by the pressure maintained in the annular grooves 28 in the inner faces of said plates.

As hereinbefore stated, the meshing of the ribs or teeth at a point immediately below the lower end of outlet passage 35 compresses the fluid at this point and the relatively small portion of fluid which passes downwardly between the teeth or ribs, due to slight clearance therebetween, will pass the apex of the triangular portion 48 of the casing 10 and exert an expansive force against the upper faces of the ribs or teeth to the sides of said triangular portion 48, thereby assisting the rotors in their rotary movement and consequently increasing the efficiency of the compressor.

The pressure of the air within the fluid separator is directed upon the body of oil that is constantly accumulating in the chamber 42 and while the compressor is in operation a portion of this oil will be forced through pipe 44 and from thence through branch pipes 45 into the passages 29 through the rotors and this oil passes into the recesses 30 to pack and lubricate the joints between the outer faces of the ribs or teeth on the rotor and the inner surfaces of the walls of the chambers 11 and likewise this liquid packing enters the annular grooves 32 and branch grooves 33 to pack the joints between the ends of the rotors and the inner surfaces of the end walls of the rotor chambers.

A compressor of my improved construction is comparatively simple, comprises relatively few parts, can be operated with the expenditure of comparatively little power, and is very effective in performing its intended functions.

It will be readily understood that minor changes in the size, form and construction of the various parts of my improved rotary air compressor may be made and substituted for those herein shown and described, without departing from the spirit of my invention, the scope of which is set forth in the appended claims.

I claim:

1. In a fluid compressor, a housing, a pair of rotors arranged for operation therein, which rotors have interengaging peripheral portions, means for delivering air into the rotor chambers at points below the axes of the rotors, there being a compressed air outlet leading from a central point between the rotor chambers, packing plates yieldingly arranged in surface contact against said rotors at one end thereof, and in overlapping sealing engagement with each other, and means for delivering fluid pres-

sure from the high pressure side of the compressor to the rotor chambers behind said plates.

2. In a fluid compressor, a housing, bearings arranged in pairs on said housing, caps closing the outer ends of said bearings, rotors journaled in said bearings, said rotors having interengaging peripheral portions, means for admitting air to the rotor chambers below the point of engagement between the peripheral portions of said rotors, there being a compressed air outlet leading through the casing from the central point between said rotors, packing plates yieldingly arranged in surface contact against said rotors at one end thereof, and having overlapping sealing engagement with each other, and means communicating with the high pressure outlet for maintaining fluid pressure behind said plates.

3. In a fluid compressor, a housing provided with a pair of rotor chambers, rotors arranged for operation in said chambers, which rotors have interengaging peripheral portions, means for admitting air at separate points to the lower portions of said rotor chambers, said points being circumferentially displaced with respect to the zone of engagement between the rotors, there being a single compressed air outlet leading from a central point between the rotor chambers outwardly from the upper portion of the casing, and freely movable packing plates yieldingly arranged against said rotors at one end thereof and packing means arranged in the peripheral faces of said plates.

4. In a fluid compressor, a housing provided with a pair of rotor chambers, rotors arranged for operation in said chambers, which rotors have interengaging peripheral portions, means for admitting air at separate points to the lower portions of said rotor chambers, and at points circumferentially displaced with respect to the zone of engagement between the rotors, there being a single compressed air outlet leading from a central point between the rotor chambers outwardly from the upper portion of the casing, and said rotors being provided in their outer faces with channels which communicate with and are supplied with liquid by a series of longitudinal bores annularly arranged in the respective rotors, thereby forming a liquid seal between the outer faces of said rotors and the surfaces of the rotor chambers.

5. In a fluid compressor, a housing provided with a pair of connected rotor chambers, a substantially triangular block arranged between the lower portions of the rotor chambers, rotors arranged for operation in said rotor chambers, which rotors are provided with interengaging peripheral portions, there being air inlet passages

formed through said triangular block and leading to the lower portions of the rotor chambers, and there being a compressed air outlet passage leading through the housing from a point between the upper portions of the rotor chambers.

6. In a fluid compressor, a housing, a pair of rotors arranged for operation therein, which rotors have interengaging peripheral portions said rotors being provided in their ends with annular grooves and series of radial channels leading from said grooves and designed to receive liquid and form concentrical and radial liquid seals, and means for delivering air into the lower portions of the chambers in which the rotors operate, there being a compressed air outlet passage leading from the rotor chambers, and counterbalanced packing plates arranged against said rotors at one end thereof said packing plates having overlapping meeting edges.

7. In a fluid compressor, a housing, a pair of cooperating fluid compressing rotors arranged for operation therein, packing plates, arranged in surface contact against said rotors at one end thereof, means for delivering fluid pressure from the high pressure side of the compressor against the outer faces of said packing plates, and said rotors being provided in their outer faces with channels which are in communication with a series of longitudinal bores formed in the respective rotors for maintaining a liquid seal between the surfaces of said rotors and the surfaces of the rotor chambers.

8. In a fluid compressor, a housing provided with a pair of rotor chambers, rotors arranged for operation within said chambers, packing plates yieldingly arranged against said rotors at one end thereof said packing plates having free peripheral engagement, and means for delivering high pressure fluid compressed by said rotors to the rotor chambers behind the packing plates therein.

9. In a fluid compressor, a housing, cooperating rotors arranged for operation therein, packing plates yieldingly arranged against said rotors at one end thereof and having free peripheral engagement with each other, packing means carried by the peripheral portions of said packing plates, and means for delivering high pressure fluid to the rotor chambers behind said plates.

10. In a fluid compressor, a housing, cooperating rotors arranged for operation therein, packing plates yieldingly arranged against said rotors at one end thereof and provided with annular passageways for forming a liquid seal between the ends of said rotors and the respective plates, packing means carried by the peripheral portions of said packing plates, means for delivering fluid pressure to the rotor chambers behind

said plates, and means for regulating the pressure of said fluid.

11. In a fluid compressor, a housing, a rotor, a packing plate arranged for yielding contact with the side face of said rotor, said packing plate being spaced from said housing said rotor being provided at its ends with annular grooves and series of branch grooves extending radially from

said annular grooves to form liquid packing for the ends of said rotor, means for delivering fluid pressure behind said packing plate to yieldingly hold the same against said rotor, and means for regulating the fluid pressure admitted behind said packing plate.

In testimony whereof I hereunto affix my signature, this 24th day of July, 1919.

JOHN O. CARREY.
